UNITED STATES PATENT OFFICE.

JOHN ZEBLEY, OF PHILADELPHIA, PENNSYLVANIA.

DESIGN FOR FRINGE.

SPECIFICATION forming part of Design No. 15,086, dated June 17, 1884.

Application filed April 2, 1884. Term of patent 3½ years.

To all whom it may concern:

Be it known that I, JOHN ZEBLEY, of Philadelphia, in the county of Philadelphia, and in the State of Pennsylvania, have invented a certain new and useful Design for Fringe for Window-Shade Trimming; and I do hereby declare that the following is a full, clear, and exact description thereof, reference being had to the accompanying drawing, in which is shown my new design.

My invention embraces a design for fringe, which shows as a heading two rovings, A and B, in parallel lines, strands C in pairs, united at their points of intersection with the lower roving, B, all substantially as shown in the drawing. Below, and depending from the roving B, are the loops D, from each of which

depends the tassel E, substantially as shown in the drawing.

Having thus fully set forth the nature of my invention, what I claim as new is—

The design for a fringe, showing the parallel rovings A and B, the strands C, extending between the rovings, plain loops D, dependent from roving B, and tassels E, pendent from the loops, substantially as shown.

In testimony that I claim the foregoing I have hereunto set my hand this 21st day of March, A. D. 1884.

JOHN ZEBLEY.
